(57) **CLAIM**

The ornamental design for a bottle, as shown and described.

DESCRIPTION

FIG. 1 is a top, front and left side perspective view of a bottle showing our new design;

FIG. 2 is a front elevational view thereof, the back elevational view being identical thereto;

FIG. 3 is a left side elevational view thereof, the right side elevational view being identical thereto;

FIG. 4 is a top plan view thereof; and,

FIG. 5 is a bottom plan view thereof.

The broken lines in the drawings depict portions of the bottle that forms no part of the claimed design.

1 Claim, 3 Drawing Sheets
